UNITED STATES PATENT OFFICE.

MICHAL J. SASGEN AND LOUIS SIMONSEN, OF CHICAGO, ILLINOIS, ASSIGNEES TO GRAND SPECIALTIES COMPANY, OF CHICAGO, ILLINOIS, A CORPORATION OF ILLINOIS.

WINDOW LOCK.

Application filed July 2, 1923. Serial No. 649,031.

To all whom it may concern:

Be it known that we, MICHAL J. SASGEN and LOUIS SIMONSEN, citizens of the United States, and residents of Chicago, in the 5 county of Cook and State of Illinois, have invented certain new and useful Improvements in a Window Lock, of which the following is a specification.

Our invention relates to improvements in 10 window locks and has special reference to the provision of a window lock of simple construction which shall be capable of being manufactured at a relatively low cost; which shall be capable of adjustment within a limited 15 amount to fit windows having frames of different thicknesses; which shall be provided with a non-marring friction shoe; which shall effectively prevent the opening of either the upper sash or the lower sash 20 beyond the set amount; and which shall be associated with a fixed stop or projection, so arranged that when the lower sash is lowered to its closed position the device will automatically be thrown to its locking position.

A particular feature of our invention relates to the ease of adjustment of the strut to fit different windows.

Our invention will be more readily understood 30 by reference to the accompanying drawings forming part of this specification and in which:

Figure 1, is a fragmentary vertical section of a window equipped with a lock made 35 in accordance with our invention.

Figure 2, is a fragmentary elevation of the inner side of the window.

Figure 3, is a top plan view of the lock.

Figure 4, is a longitudinal section thru 40 the arm of lock on the line 4—4 of Figure 1; and

Figure 5, is a cross section on the line 5—5 of Figure 1.

As shown in the drawings, our improved 45 window lock is particularly adapted to be secured upon the top rail or bar of the lower sash and to engage the upper sash so that when the lock is in operative position the two sashes cannot be moved toward each other even though one or the other is more or less open, while on the other hand the sashes can be moved to separate them. In other words the window cannot be opened

beyond the locked relation but may be closed. Our improved window lock comprised in a 55 strut or arm 1, adapted to be pivotally mounted at one end preferably on the top bar of a lower sash to swing from and toward the upper sash and provided with a shoe or foot for contact with the side bar 60 of the upper sash to brace the two sashes against movement toward each other.

Preferably the arm or strut 1 is mounted at one end on a pivot 2 secured in a base member 3. The base member 3 is formed of 65 sheet metal and has a flat bottom 4 to rest upon the top bar 5 of the lower sash 6 and is provided with a down-turned outer end 7 for contact with the face of the bar 5. The bar is provided in the inner end of the 70 bottom 4 with a hole for receiving a fastening screw 8 and the down-turned outer end is provided with a hole for a second fastening screw 9.

Near the outer end of the base we provide 75 a pair of upstanding projections 10 formed up out of the metal of the base and which carries the pivot 2 which is preferably in the form of a removable screw. Preferably the portions out of which the projections 80 10 are formed are bent inwardly close to the top surface of the base 4 and then upwardly, as best shown in Figure 2, the upper parts being parallel and spread apart just sufficient to receive the strut 1 between them. 85

The strut 1 is preferably though not necessarily made adjustable as to length so that in applying the device to a window the free end of the strut can be properly engaged with the upper sash when the base is properly attached to the lower sash with the down-turned outer end in contact with the face of the lower sash, as shown in Figure 1.

For this adjustability we preferably make 95 the strut 1 of a single thickness member 11, one end of which is pivotally mounted on the pivot 2 between the projections 10 and the other end of which is provided along its longitudinal center line with a series of 100 holes 12. To complete the strut 1 we provide a bifurcated member 13 adapted to be secured to the free end of the arm 11 and preferably provided with a shoe or pad 14 which I prefer to make slightly yielding for 105 frictionally engaging the upper sash. The

member 13, as shown in Figure 4, is preferably made of a sheet metal strip, its two ends 15 bent back into parallel relation and spaced apart to receive the free end portion 5 of the arm 11 between them. We provide these parallel ends 15 with at least two holes each for receiving fastening screws 16 and spaced to register with the holes in the arm 11. It will readily be seen that with the 10 fastening holes made as described the strut can be readily changed as to length. In the drawings we have shown the strut as short as it can be made, and it will be readily seen that it can be lengthened by removing the 15 screws 16, sliding the part 13 outwardly and entering the screws again through other holes in the arm 11.

As shown, we preferably curve the strut 20 edgewise to cause the engaging face 17 of the strut to properly contact with the upper sash and in consequence of this the series 25 of fastening holes in the arm 11 and the member 13 are likewise on a curved line, substantially following the longitudinal central line of the strut.

We preferably slightly curve the contacting 30 face 17 of the end of the strut and provide it with transverse V-ridges 18 to assist the gripping of the upper sash.

35 In securing the yielding shoe 14 on the end of the member 13 we preferably form it and secure it by the well known vulcanizing process, forming it to enclose the free end of the member 13 which end is preferably made wider than the body, as best shown in Figure 4.

The curved strut besides setting the free 40 end properly against the upper sash assists in automatically throwing the device to locking position when the lower sash is being lowered to its closed position. For this purpose we provide a stop 19 secured to the window frame and projection out into the path of the strut when the same is swung 45 out to inoperative position, as shown at 20. For instance, suppose that the lower sash has been raised to the position shown at 21 and the strut thrown to locking position, as shown at 22, the two sashes will be locked 50 against movement toward each other but will be free to be moved relatively apart, in other words the lower sash can be readily closed, as the strut will swing freely up. Now we will presume that the 55 strut has been swung out to the inoperative position, as shown at 20, and when the strut is in this inoperative position, should the lower sash be lowered to closed position, the strut will come in contact with the 60 projection 19 and will be caused to swing over toward the upper sash. The projecting convex back of the strut, as illustrated by the dotted line 23, will cause the strut to be pushed over far enough so that it will 65 drop automatically into locking position and

prevent the window being opened without first lifting the strut. The strut being curved as described permits the strut to be swung back, while the lower sash is in the closed position, and rest in such operative 70 position against the stop projection 19, as shown in dotted lines in Figure 1. The pivot 2 being readily removable permits the ready adjustment of the length of the strut to fit a window to which it is being applied. 75 The removal of the pivot 2 permits the removal of the strut and while removed it can readily be lengthened or shortened to suit.

As many modifications of our invention 80 will readily suggest themselves to one skilled in the art, we do not limit or confine our invention to the specific details of construction and operation herein shown and described.

We claim:

1. A window lock comprising a stiff strut adapted to be pivotally mounted upon the lower sash, the strut provided with a yielding pad for frictional contact with a part above the lower sash for preventing the free raising of the sash, and said strut being changeable as to length for fitting different windows. 90

2. A window lock comprising a stiff strut adapted to be pivotally mounted upon the lower sash, the strut provided with a yielding pad for frictional contact with a part above the lower sash for preventing the free raising of the sash, the strut being made of two parts and means for connecting the two parts in different longitudinal relations for changing the length of the strut. 95

3. In a window lock of the kind described, a stiff strut adapted to be pivotally mounted upon the lower sash, the strut provided with a yielding pad for frictional contact with a part above the lower sash for preventing the free raising of the sash, the strut being made of two parts, the two parts each having a series of holes for receiving connectors and adapting the two parts to be secured together in different relations for adjusting the length of the strut. 100

4. In a window lock of the kind described, a locking strut adapted to be pivoted to the top of the lower sash to swing from and toward the upper sash, and means for automatically causing the strut to be swung over into contact with the upper sash as the lower sash is brought down to its closed position. 115

5. In a window lock of the kind described, a window lock comprising a strut adapted to be pivotally mounted upon the lower sash, the strut provided with a yielding pad for frictional contact with a part above the lower sash for preventing the free raising of the sash, the strut being made of two parts, and a fixed stop on the window frame adapted to engage the strut, if it is in inoperative position, as the lower sash is 125 130

brought down to closed position, and cause same to be thrown over into operative position.

6. In a window lock of the kind described, a curved strut, means for pivotally mounting the strut at one end adjacent to the inner edge of the lower sash, the free end of the strut adapted to frictionally contact with the side member of the upper sash, a fixed stop on the window frame in the path of the strut when thrown out of operative position and adapted to engage the convex curved edge of the strut as the lower sash is brought down to closed position to swing the strut over toward the upper sash into un-

balanced condition, as and for the purpose specified.

7. In a window lock of the kind described, a base adapted to be secured on the top of the top rail of a lower sash, a strut, means for removably pivotally mounting the strut on the base close to the inner face of the said rail, the free end of the strut adapted to frictionally contact with the upper sash, and means for adjusting the length of the strut.

Signed at Chicago, Illinois, this 23rd day of June, 1923.

MICHAL J. SASGEN.
LOUIS SIMONSEN.
